UNITED STATES PATENT OFFICE.

JAMES BARKER, OF PHILADELPHIA, PENNSYLVANIA, ASSIGNOR TO MARY EMMA BARKER, OF RYDAL, PENNSYLVANIA.

DESIGN FOR A CHAIR-PEDESTAL.

50,900.

Specification for Design.

Patented June 12, 1917.

Application filed April 18, 1916. Serial No. 92,049. Term of patent 14 years.

To all whom it may concern:

Be it known that I, JAMES BARKER, a citizen of the United States, residing in Philadelphia, Pennsylvania, have invented a certain new, original, and ornamental Design for a Chair-Pedestal, of which the following is a specification, reference being had to the accompanying drawing, which shows a perspective view of the ornamental design for a chair-pedestal forming the subject-matter of my invention.

The body part of the structure, though tapering slightly, is substantially cylindrical; the top thereof comprising a cap-like portion with sides having the contour of an

ogee curve, and the rounded bottom of the same is slightly larger than the part of the body which it joins; the body portion tapers slightly, the bottom flaring outwardly in a curve to join the base, and the latter has a raised annular edge, the outer margin of which is curved. The central portion of the body has a series of ornamental scallops, joining a continuous annular band, formed in relief upon the surface of the same.

I claim:

The ornamental design for a chair pedestal, substantially as shown and described.

JAMES BARKER.
